UNITED STATES PATENT OFFICE.

ALEC J. GERRARD AND LEROY F. HINTZ, OF CHICAGO, ILLINOIS; SAID HINTZ ASSIGNOR
TO SAID GERRARD.

BELT-SLITTING MACHINE.

Application filed April 29, 1924. Serial No. 709,798.

To all whom it may concern:

Be it known that we, ALEC J. GERRARD and LEROY F. HINTZ, respectively a subject of the King of Great Britain and a citizen of the United States, residing at Chicago, in the county of Cook and State of Illinois, have invented certain new and useful Improvements in Belt-Slitting Machines; and they do hereby declare the following to be a full, clear, and exact description of the invention, such as will enable others skilled in the art to which it appertains to make and use the same.

This invention relates to a belt stripping or slitting machine and has for its object to provide a device of this character which will be simple in construction, comparatively inexpensive to manufacture, and more efficient in use than those which have been heretofore proposed.

With these and other objects in view the invention consists in the novel details of construction and combinations of parts as will be more fully hereafter disclosed and particularly pointed out in the claims.

Referring to the accompanying drawings, forming a part of this specification in which like numerals designate like parts in all the views,

30 Fig. 1 is a front elevational view of the machine partly in section;

Fig. 2 is a sectional view taken on the line 2—2 of Figure 1, and looking in the direction of the arrows;

35 Fig. 3 is an end elevational view of the machine; and

Fig. 4 is a sectional view taken on the line 4—4 of Figure 1, and looking in the direction of the arrows.

40 In the drawings, 1 indicates any suitable base having at one end an upwardly extending lug portion 2 and provided at its other end with a vertically disposed frame member 3 having an overhanging arm 4. The lug 2 and the vertical frame 3 form bearings for the shaft 6 which is provided with the gear 7 and the operating handle 8 at one end. At the other end of shaft 6 is mounted a knurled feeding roll 10.

50 Disposed above the feed roll 10 and in the same plane therewith is a second knurled feed roll 11 rigidly secured on the end of a shaft 12 provided at its opposite end with a gear 13 meshing in the driving gear 7. Be-

yond said gear 13 the shaft 12 is provided with a loose bearing in the frame 3.

Near the knurled feed roll 11, the shaft 12 passes through a spring pressed guide member 16 adapted to slide in the bore 17 of the overhanging arm 4. A portion of this bore is threaded to accommodate the hand screw 18 by means of which tension may be placed upon the spring 19 interposed between the guide member 16 and the hand screw 18, all as will be clear from Figure 1.

Disposed between the shafts 6 and 12 and rigidly secured to the lug 2 and the frame member 3 is a flat plate like member or table 20 provided with an opening therein through which protrudes the lower feed roll 10 and a cutter 21, the said cutter being rigidly secured to the lug 2 as shown. The plate 20 is also provided with the slit 25 within which slides the adjustable straight-edge or guide member 26 provided with the upturned edge 27 against which the belt to be trimmed is positioned. One end of the member 26 is downturned to form a head 28 adapted to slide along the front edge of the plate 20 and also to prevent the main body portion of the straight-edge member 26 from wobbling while the belt is being trimmed. A section 29 of the plate 20 is upturned to form a guard for the meshing gears 7 and 13.

The plate 20 may be provided with scale markings 30 adjacent the slit 25 permitting the straight edge 26 to be quickly set as desired and thereupon clamped firmly to the plate 20 as by the set screw 31.

The loose bearing for shaft 12 formed in the frame 3 comprises a bore 35 having a diameter slightly larger than the diameter of the said shaft. A locking pin 36 located transversely of said bore 35 and extending partially within the upper portion thereof coacts with a circumferential groove 37 located near the end 38 of the shaft 12 and thus serves to prevent longitudinal displacement of the said shaft.

The operation of the machine is as follows: Supposing a belt of 5½ inches in width after continued use has become nicked, cut, or otherwise injured along the edges but has a body portion which is still good. Further suppose there is use, or need, for a belt of say 4½ inches in width. In such a case the straight-edge member 26 would be

clamped to the plate 20 at a scale marking which would correspond to the numeral "5" as shown in Figure 2. The side of the belt would then be positioned along the upper turned edge 27 of the member 26 and the end of the belt would be advanced toward the feed rolls 10 and 11. Upon turning the handle 8 the feed rolls would take hold of the belt and upon continued turning of the handle the belt would be fed through the machine.

As the belt is forced through the machine, however, the knife or cutter 21 slits the belt and thereby cuts a strip therefrom. After passing the 5½ inch belt through the machine the cutter 21 will have cut off one of the injured edges and so produced a belt of 5 inches in width provided with one good edge but still having one of the original injured edges.

The straight-edge member 26 is then reset and clamped to the plate 20 at such a scale marking as would position the said straight-edge a distance of 4½ inches from the cutter 21. Then the belt is again passed through the machine but this time the good edge is in contact with the member 26, thus permitting the remaining injured edge of the belt to be trimmed off by the cutter, and so producing a belt of 4½ inches width with good edges.

It will be observed that the guide 16 for the shaft 12 does not extend below the lowermost portion of the upper feed roll 11, and it will be further observed that the feed roll 11 may be raised to accommodate belts of different thicknesses. The vertical movement of the feed roll 11 and the end of the shaft to which it is fastened is due to the loose bearing 35 in which the opposite end 38 of the said shaft is journaled. In other words it will be seen from Figure 1 that the parts of the machine are so proportioned and positioned that when no belt is passing through the device the weight of the shaft 12 will cause the teeth of gear 13 to be fully in mesh with the teeth of the driving gear 7, and the locking pin 36 will occupy fully the groove 37 of said shaft 12. Stated in other words the downward pressure exerted upon the end of shaft 12 carrying the knurled feed roll 11 will be transmitted through the gears 7 and 13 acting as a fulcrum to the end 38 of the said shaft and there create an equal and opposite upward pressure against the locking pin 36.

When a belt is introduced to the machine and the knurled feed rolls 10 and 11 take hold and propel the said belt through the machine, then the upper roll 11 and consequently the end of the attached shaft 12 will be raised approximately the thickness of said belt. It will be seen that provision must be made for this shaft displacement and therefore the bore 35 is made slightly

larger than the diameter of the shaft 12 journaled therein. This loose bearing is not however, so large that the locking pin 36 will not at all times engage a portion of the circumferential groove 37.

It has been found that the use of cutting or trimming knives heretofore when used with or without straight edges as guides has caused considerable difficulty, loss of time, and generally required the services of two shop employees. At best, a belt trimmed in the old way was a laborious task. With the aid of this simple mechanism, on the other hand, a belt of any material such as leather, canvas, rubber, balata, etc. can be quickly and easily trimmed by a single employee. Further, the completely trimmed belt will be true and more neatly formed as a result of the use of this mechanism.

It is obvious that those skilled in the art may vary the details of construction as well as the arrangement of parts without departing from the spirit of the invention, and therefore it is not desired to be limited to the foregoing disclosure except as may be required by the claims.

What is claimed is:

1. In a machine for trimming belts the combination of a cutter; a stationary driving shaft; a pivoted driven shaft geared thereto between said pivot and said cutter; means to propel a belt past said cutter; and means to vary the pressure of said propelling means.

2. In a machine for trimming belts the combination of a cutter; a driving shaft; a tiltable shaft geared thereto between said pivot and said cutter; means comprising a pair of feed rolls carried by said shafts to propel a belt past said cutter; and means to vary the pressure of said propelling means.

3. In a machine for trimming belts the combination of a cutter; a driving shaft; a tiltable shaft geared thereto between said pivot and said cutter; means including a feed roll mounted on each of said shafts to propel a belt past said cutter; and means to vary the pressure of said propelling means.

4. In a machine for trimming belts the combination of a frame; a shaft supported at both ends in said frame; a tiltable shaft loosely journaled at one end only in said frame; a cutter; means to propel a belt past said cutter; means to guide said belt to said propelling means; means to drive said propelling means; and means to vary the pressure of the propelling means.

5. In a machine for trimming belts the combination of a frame; a shaft supported at both ends in said frame; a tiltable shaft loosely journaled at one end only in said frame; a cutter; means carried by said shafts to propel a belt past said cutter; means to guide said belt to said propelling

means; means to drive said propelling means; and means to vary the pressure of the propelling means.

6. In a machine for trimming belts the combination of a frame; a shaft supported at both ends in said frame; a tilttable shaft loosely journaled at one end only in said frame; a cutter; means to propel a belt past said cutter; means to guide said belt to said propelling means; means to drive said propelling means; and means supported by the free end of the tilttable shaft to vary the pressure of the propelling means.

7. In a machine for trimming belts the combination of a frame; a power shaft supported in said frame; a lower feed roll mounted on said shaft; a tilttable second shaft loosely journaled at one end only in said frame; an upper feed roll mounted on said second shaft; means supported by the free end of said second shaft to force said upper feed roll toward said lower feed roll; a cutter; means to guide a belt to said cut-

ter; and means to operate said feed rolls to propel the belt past said cutter.

8. In a machine for trimming belts the combination of a frame; a table provided with a slot supported by said frame; a power shaft supported in said frame; a lower feed roll mounted on said shaft; a tilttable second shaft loosely journaled at one end only in said frame; an upper feed roll mounted on said second shaft; means provided with a beveled orifice through which said second shaft passes for supporting said second shaft and adapted to force said upper feed roll toward said lower feed roll; a cutter; means adjustable in said slot to guide a belt to said cutter; and means to operate said feed rolls to propel the belt past said cutter.

In testimony whereof we affix our signatures.

ALEC J. GERRARD.
LEROY F. HINTZ.
